United States Patent Office.

SYLVESTER H. ROPER, OF BOSTON, MASSACHUSETTS.

Letters Patent No. 94,135, dated August 24, 1869.

IMPROVEMENT IN KNITTING-MACHINE.

The Schedule referred to in these Letters Patent and making part of the same.

To all whom it may concern:

Be it known that I, SYLVESTER H. ROPER, of Boston, in the county of Suffolk, and State of Massachusetts, have invented certain Improvements in Knitting-Machines; and I do hereby declare that the following, taken in connection with the drawings which accompany and form part of this specification, is a description of my invention sufficient to enable those skilled in the art to practise it.

My invention relates to an improved combination of separately moving latch-needles with separately-moving sinkers co-operating therewith to press down and draw off from the bobbin a sufficiency of yarn for each stitch, and to means for graduating the distance to which the sinkers may descend; to a novel automatic widening-mechanism; to a provision by which the loop upon the needle shall of itself, at a proper period, hold back the latch and prevent its flying forward before the bobbin receives its yarn for the next stitch; to the means for shifting the thread-guide and sinker-cam relatively to each other, that the former may always be kept immediately in advance of that sinker which is next to depress the thread, in each reciprocating-movement of those parts; to an improved tension-device and improved means for adjustment of the same; and to other details hereinafter more particularly set forth.

My machine is intended mainly for knitting fine work and for widening the same at either or both selvages.

Figure 1 represents a front view of my machine, the tension-apparatus and bobbin-spindle not being fully displayed.

Figure 2 is a top view.

Figure 3 is a cross-section, taken on the line $x x$ of the preceding figures, looking toward the bobbin; and

Figure 4 is a cross-section on the same line, looking toward the widening-mechanism.

A is the supporting-frame, and B a surmounting bed-plate secured thereon, a grooved space, c, between them receiving and permitting the reciprocation of the latch-needles, and longitudinal ways in B permitting the reciprocation of the traversing-plate D, which receives its motion directly from the connecting-rod E, which is firmly secured to the endless belt or chain F, which passes over the pulleys G G', both of which are supported on the hanger H projecting from the side of A, and the former of which is driven by the hand-crank I, or in any other suitable manner.

The belt is preferably given such a degree of tightness as will be sufficient to drive the machine when no special obstruction or derangement occurs, but will allow it in such an event to slip upon without being driven by the driving-pulley.

To the under side of plate D is adjustably secured,

by means of screws K and washers, the cam-piece L, shown in dotted lines in fig. 2.

This cam I prefer to make in the general form shown, its thickness at 1, 2, and 3, being about equal to the full breadth of the cut in the needle-stock, and the curvature 4 being designed to allow the needle a very brief rest, after it has completed its forward movement, and then a gradual commencement of its back motion at the period when the sinker is down to its lowest point of movement and with its fullest pressure and commencing to rise, and hence the strain on the yarn is avoided which otherwise would occur, if before the rising of the sinker the needle were to recede and pull back its yarn. The rising of the sinker at once relieves the strain of the loop. This provision is necessary in knitting fine goods from inelastic single-spun yarn.

That portion of the cam shown at 5 and 6 is designed for another special and important purpose.

In most, if not all, latch-needle machines, latch-openers are employed to insure that the latch shall be thrown back and the hook uncovered at the period when the yarn is to be delivered to the hook for forming the next succeeding stitch.

If the latch-opener be not employed, there would be no certainty that the latch would remain thrown back, and whenever a failure should occur the result must be a lost stitch and defective goods.

Now, the straight portions 5 and 6 so act relatively to the needle during its forward or advancing-motion as to arrest it momentarily and give it a very slight period of rest just at that juncture when the loop last formed thereon, after having forced back the latch, rests upon and embraces it, confining it down upon the needle-shank, and thereby positively preventing the latch from flying forward from any cause and covering the unthreaded hook.

A hole in plate D, beneath each of the washers at K, and made somewhat larger than the screw which holds the washer, permits the slight adjustment of the cam-piece L to time this period of rest properly relatively to the movements of the other parts of the mechanism, and also a forward and back adjustment to render certain the drawing of the last-made loop entirely through the preceding one.

The wavy portions of the cam, as shown at M M, are for the purpose of tightening or shaking down the loops of the stitches of the last course upon those of the course being formed.

N N are posts erected upon the plate D.

These posts are screw-threaded at their tops and support a plate, O, which is secured thereon by nuts 7 8, so that it may be raised or lowered, when desired, to vary the point to which the sinkers may be caused to descend, said sinkers being operated by the edge

of plate O, and by a cam-projection on a carriage, P, supported upon and arranged to slide on the plate O, as shown, the sinkers Q being arranged to slide in appropriate grooves in the vertical fixed upright R.

The yarn-deliverer S is adjustably secured to the downward projection T of the yoke U, the latter being secured to the sliding-plate or carriage V.

On the top surface of the cam-carriage is secured a toothed rack, 9, and on the plate V is a corresponding rack, 10.

Affixed to plate O is a peculiar pinion, 11, located so that a portion of its teeth (being those of its shorter radius) shall mesh with the teeth of rack 9, and the other portion (being those of the longer radius or farthest distant from the axis of the pinion) shall mesh with the teeth of rack 10.

Upon the stationary frame or bed-plate B are erected fixed uprights or stops 12, against which (during the reciprocations of plate D, and the parts which it carries) a projection or pin, 12', on the under side of thread-carrier slide V, strikes, for the purpose of having the further traverse of the thread-carrier arrested while the plate D continues its movement.

This continued movement of plate D, while the rack 10 remains stationary, carries with it the pinion 11, which is geared with the rack 10 upon the thread-carriage and causes the rotation of the pinion, which thus drives the other rack and consequently the sinker-cam slide.

By these means the thread-carrier and sinker-cam are always brought into proper relative position as regards each other at the end of each traverse, and the delivery-eye of the thread guide is also brought into proper position relatively to that sinker immediately adjacent to it, which will insure its sinking the thread just delivered to a needle.

Instead of the pinion and racks 9 10, other devices may be used as modifications, or as equivalents, as, for instance, a lever with unequal arms, and a sliding box operated by either end of the lever, the boxes being secured to the carriages in lieu of the racks.

My thread-tension device is made as follows, being sustained upon a rod or post, 13, removably attached to the thread-carrying frame or slide. To the top of this post I pivot a vertically-swinging lever, 14, to the end of which I connect, at one of the openings 15, provided therefor, a spiral spring, 16, whose lower extremity is secured to a sleeve or slide, 17, arranged to be moved up or down on the post at will, and to be adjusted and secured in place by the screw 18. The other arm of lever 14 is provided with an eye to receive the thread, as shown. A long wire, 19, having an eye or loop at its farthest extremity, is permanently attached to this lever 14, and a thin, very flexible spring, 20, is fastened to the wire 19, as shown, and has at its extremity also a loop or eye for the thread. A frictional pad, 21, covered with cloth, leather, rubber, or other suitable material, to give a gentle drag to the thread, is secured upon the wire 19 at a point between the two eyes on the springs 19 and 20.

When the pull upon the yarn in the act of knitting is the greatest, as, for instance, when the sinker is in the act of pressing down the yarn, it is necessary, with the very delicate yarn used in making fine work, that the resistance against the free delivery of the yarn should be as little as possible, although at other times it needs to be sufficient to insure the return of all the slack yarn through the thread-carrier.

By my improved apparatus, the normal position of the yarn, when a take-up and resistance against too free a delivery are needed, is about as shown in fig. 3. When, however, the pull upon the yarn takes place, the eye on spring 20 is drawn down, so that it lies in the same line with the pad 21, and the eye on the wire 19, or sufficiently so to relieve the thread from its contact with the pad and permit its free delivery.

The widening-apparatus is constructed as follows:

To the plate O is secured a projection, 21, to which is pivoted, as shown at 22, at slotted piece, 23, having a series of holes therein to receive the pin 24, which, passing through another projection, 24', serves to hold the piece 23 in any desired position.

When the piece 23 is in the position shown in fig. 2, it performs no duty, because its slot or opening during the reciprocations of the plate does not actuate any of the widening-mechanism.

When, however, the piece 23 is turned outward on the pivot 22 and then secured in that position by pin 24, so that the slot is not parallel with the reciprocations, but inclined thereto and to the plate, then the movement of plate O in the direction of the upright pin 25 (that is, toward the left of the machine) causes a forward movement of the sliding rack 26, by reason of the action of the wall of the inclined slot against the pin.

This rack is supported in a bracket, 27, and the return of the piece 23 causes the return movement of the rack.

In proper bearings 28 28 is hung a horizontal shaft, 29, on which is a loose gear, 30, having teeth on only a portion of its edge, and having also an arm, 31, with an impelling pawl, 35, and spring thereon.

Secured on the shaft, and side by side with this loose gear, is a ratchet-wheel, 34, whose backward movement is prevented by a spring-click.

Upon the shaft is placed a screw-threaded sleeve, 36, feathered with the shaft, so that while it must revolve with it, yet it is free to slide longitudinally thereon. This sleeve is provided with radial arms or wings 37 projecting therefrom, and whose edges are barely thick enough to insure their acting against the rear end of one needle-stock without risk of accidentally touching an adjacent one.

A stationary spring, 38, having a small projection, or section of a nut, 39, to enter the grooves of the screw, effects the longitudinal movement of the sleeve during its revolution.

The operation of these parts is as follows:

When it is desired to widen by bringing into action any of the needles which have been pushed back beyond the action of the needle-operating cam, the wings having been so placed as in their next movement to push forward the needle next required for use, and the slotted piece adjusted to an inclination as before stated, the movements of the piece 23 push forward the slide-rack 26, which, giving motion to the segmental gear 30, actuates the ratchet-wheel, and thereby rotates the shaft, and consequently the radial wings, until one of them shall bear against the rear of the next needle-stock, and force it forward into position for action.

The return-movement of the rack does not rotate the shaft, but merely brings the segmental gear back ready for its next action.

The partial rotation of the winged sleeve advances it on its shaft, so that at the proper time it may be in position by further rotation to bring one of its wings so as to push forward the next needle in order.

The frequency with which the reserve needles shall be brought into action one after another will depend upon the degree of inclination given to the slotted piece, as the greater the inclination the further around will the rack rotate the shaft and sleeve.

This frequency will also be increased proportionately to the number of wings on the sleeve.

Generally, it will be desirable to widen gradually by bringing a new needle into play at, say, every fourth, sixth, or eighth course.

It will be observed that in the illustrations we have shown but few needles, and also that we have shown the widening-apparatus for widening on one side only of the fabric.

In practice, we employ any appropriate number of needles, and duplicate the widening-apparatus so as to widen at both selvages.

To drive a knitting-machine by a crank is very objectionable, as there is no possibility of attaining that uniform velocity required during the action of the needles and the formation of the stitches.

To avoid, therefore, this variable and varying velocity, which ranges from the zero or dead points to the other extreme, I employ two wheels, G and G', and an endless belt or chain stretching from one to the other, and then connect rigidly to such belt a metal piece or pin, 42, having a journal thereon which the connecting-rod centres, the rod also centring on a pivot, where it is connected to the reciprocating-plate D.

This mode of driving effectually ignores the dead points, so far as the knitting-operations are concerned, as the needles and other operative parts of the knitting-mechanism are only actuated while the pin 42 (and consequently the connecting-rod) is moving in horizontal lines, and while this pin is travelling around either of the pulleys, the needles, sinkers, and yarn-guide are not in the act of knitting.

I claim the combination of a system of separately-moving latch-needles with a system of separately-moving sinkers co-operating therewith, in the manner and for the purpose described.

Also the combination, with such systems of latch-

needles and sinkers, of mechanism for adjusting simultaneously the depth of descent of all the sinkers.

Also, an automatically-rotating and travelling wing or arm, operating to bring the needles into action for widening, substantially as set forth.

Also, the means, substantially as described, for arresting the forward movement of the needles, whilst the loop is on the latch, to insure the keeping open of the hook to receive yarn for the next stitch, and then advancing them to the full extent of their forward movement.

Also, the combination, with stationary stops on the frame, of the sliding carriage of the thread-carrier, the sinker-cam carriage, and the double-acting pinion and racks, or their equivalents, the whole operating substantially as shown and set forth.

Also, the combination, with the main and auxiliary tension-springs 19 and 20, of a friction-pad on the former, so arranged and located that a slight strain upon the yarn shall cause the eyes of the springs to coincide in line with the straightened thread and relieve the same from the pad.

Also, the combination, with the tension-springs, of the lever 14 and its adjustable spring 16.

S. H. ROPER.
